UNITED STATES PATENT OFFICE

BYERS W. KADEL, OF BALTIMORE, MARYLAND

CAR DOOR MECHANISM

Application filed December 17, 1925, Serial No. 76,044. Renewed November 11, 1929.

This invention relates to car door mechanism for railway dump cars and has for its object to provide simple, rugged and reliable means for readily closing and securing hinged car doors and more especially those of the type, such as hopper doors, which swing to open position under the influence of gravity. A more specific object of the invention is to provide a mechanism in which the parts are so arranged as to ensure a high degree of efficiency under service conditions while at the same time affording convenient and effective means for utilizing a pry bar to force the door from partially closed to fully closed position.

A primary feature of the invention, generally stated, consists in providing the swinging door controlling the opening through which the lading of the car is to be discharged with a bracket having a portion which projects laterally outward so as to be adapted, when the door is in closed position, to stand in overlapping relation to a door supporting bracket secured to the side of the car; the outwardly extending portion of the bracket carried by the door constituting a guide and support for a slidable locking member adapted to cooperate with the bracket mounted on the car body and thus maintain the door in closed position.

A further feature of the invention involves the employment of a plurality of brackets one of which is rigidly mounted on the car door and the other on the side of the car body, one of the brackets being adapted to support a sliding locking member which cooperates with the other bracket to maintain the door in closed position, and each of said brackets being formed with means extending outwardly from the side of the car for operating with a removable lever to force the door to closed position.

Other advantageous features of the invention pertaining to details of construction and desirable combinations of parts contributing to ease of manufacture and efficiency of operation will appear as the invention is described in further detail.

In the accompanying drawings illustrating a preferred embodiment of the invention,—

Figure 1 is a fragmentary side elevation of a portion of a hopper car showing the invention applied thereto.

Figure 2 is a sectional view on the line 2—2, Fig. 1.

Figure 3 is an end elevation, looking toward the door, of the construction shown in Fig. 1.

Figure 4 is a detail sectional view on the line 4—4, Fig. 3.

Figure 5 is a detail plan view of the bolt 60 engaging bracket mounted on the car side.

Door locking mechanism constructed in accordance with the invention is especially suitable for application to cars of the twin hopper type and accordingly a car of that character has been illustrated in the drawings for the purpose of explaining the invention.

In the drawings, 1 designates the downwardly and inwardly inclined outer side sheet of a car hopper and 2 is the door for closing the hopper discharge opening. The door may be hinged to the car body in any usual or desired manner and preferably is of the sheet metal type having an outturned marginal flange 3. Adjacent the margin of its discharge opening the hopper may advantageously have an outwardly extending seat or shoulder 4 serving to limit the closing movement of the door and be provided with a sealing flange 5 which when the door is in closed position overlies the marginal flange 3 of the door and thus prevents the escape of fine lading.

Secured to the outer face of the door and preferably extending parallel to the free edge of the latter is a door reinforcing member 6 which may extend across and be rigidly attached to both door sections of the hopper so as to cause them to act in the usual manner as a single unit. This reinforcing member may advantageously be of flanged form, preferably being a section of commercial channel iron having its flanges extending downwardly. Riveted to the door and to the web of the reinforcing member 6 secured to the latter is a bracket 7 formed with angularly disposed webs or flanges 8 and 9 which respectively seat against the body of the door and the web of the door spreader 6. The bracket 7 extends outwardly beyond the side 101

sheet 1 of the car and intermediate its ends is offset, as at 10, to clear the marginal flange 3 of the door. The bracket is fashioned, between its outer end and the offset 10, with a housing 11 for receiving a slidable door locking member 12 which preferably is a bolt of rectangular cross section. This housing may be integral with the bracket 7 and one of its walls preferably constitutes a portion of the basal flange 8 of the bracket. The remaining walls of the housing 11 preferably extend upward from the flange 9, the latter being apertured to conform to the shape of the bolt and permit the passage of the latter. The housing 11 is positioned so that the lower end of the bolt 12 is disposed outwardly beyond the discharge opening of the car hopper, thus enabling the bracket 13 which is mounted on the car body for cooperation with the bolt to be arranged so that it cannot be injured, clogged or fouled by the lading as it is discharged from the hopper. Moreover, such a construction permits the mechanism to be provided with strong and simple means for effectively cooperating with a removable lever such as is commonly employed for forcing the door to fully closed position in case it may become bent or warped as the result of service. The bolt 12 preferably is gravity actuated so as automatically to assume locked position and may advantageously be in parallelism to the plane of the door and substantially at right angles to the axis upon which the door swings. At its outer end the bracket 7 is formed with a lug 14 serving as a seat for a removable door operating lever. This lug may, as shown, advantageously be curved or hooked so as to form a recessed seat for the prying lever and may be backed up or reinforced by a suitable rib or flange 15 if desired. It is desirable to form the upper end of the sliding locking bolt 12 with a lug 16 which projects outwardly above the lever seat lug 14 on the bracket carried by the door, as such a construction permits a removable lever to be fulcrumed on the seat 14 and brought into engagement with the lug 16 of the bolt for the purpose of moving the latter to door releasing position if difficulty should be encountered in so doing. Opposite the lug 16 the slidable bolt 12 is preferably provided at its top with an inclined face 17 which is adapted to be engaged by a rotatable cam or dog 18 mounted upon the bracket 7. This cam member is preferably pivoted to its supporting bracket by means of a flanged sleeve or thimble 19 through which and through the bracket 7 of the rivet 20 passes. While the bolt 12 tends to remain in door securing position by its own weight, the cam 18 provides positive means for preventing an accidental unlocking movement of the bolt, as will be readily understood. To strengthen the offset end of the bracket 7 so that it may effi-

ciently resist the forces to which it is subjected in service, its flange 9 may advantageously be curved or widened at its outer end, as indicated at 20, and gusset flanges 21 and 22, respectively, projecting outwardly from the flange 8, may extend across the offset 10 of the bracket. 70

The bracket 13 for cooperating with the sliding bolt 12 is rigidly secured to the car body by means of rivets 23 which extend through the side sheet 1 of the hopper. A filler 24 of the same thickness as the plate forming the door seat 4 and sealing flange 5 of the hopper is preferably interposed between the bracket and the side sheet of the car when the said door seat and sealing flange are formed upon a member attached to the side sheet. This bracket may advantageously be formed with a base plate 25 which is laterally offset intermediate its ends, as at 26, to pass around the marginal sealing flange 5 of the hopper, and it may be fashioned with an outstanding web or gusset 13' reinforcing the offset in the basal plate 26 and tying the inner end of the latter to the bolt receiving socket 27 formed at the outer end of the bracket. The portion of the basal plate secured to the side sheet of the hopper is disposed in a plane substantially parallel with the latter while the portion of the plate disposed outwardly of the sealing flange 5 is disposed in a substantially vertical plane. The socket portion 27 of the bracket 13 extends laterally of the adjacent portion of the basal plate substantially normal thereto and is preferably provided with a plurality of shoulders 28 and 29, respectively, corresponding to similar faces or shoulders 30 and 31 at the lower end of the sliding bolt 12. By this means the door 2 may be supported either in partially closed position or in fully closed position when as shown in the drawings the face 30 of the bolt engages the shoulder 28 of the bracket the door is held in fully closed position, but if the shoulder 31 of the bolt is in engagement with the shoulder 29 of the bracket then the door is maintained in partially closed position. To cause the sliding locking member 12 to be automatically retracted when the door is swung toward closed position the relatively wide upper surface of the bolt receiving socket portion of the bracket 13 preferably has its outer end 32 curved or inclined to form an approach plane for cooperating with a beveled face 33 with which the bolt 12 is provided at its lower end. The bolt receiving portion of the bracket 13 may if desired be formed with a web or flange 34 serving as a stop adapted to engage the bolt so as to limit the closing movement of the door. Since when the door is in closed position the bolt receiving portion of the bracket 13 is disposed immediately below the outwardly extending portion of the bracket or arm 7 it will be appreciated that the former 130

affords an abutment to limit sagging or drooping of the door.

Projecting laterally outward from the socket portion 27 of the bracket 13 beneath the fulcrum lug 14 of the bracket 7, is a lever seat or fulcrum member 34, preferably constituted as a lug which is indented or pierced so as to form a recess or eye for receiving a removable pry bar or lever. When such a pry bar (not shown) is brought into cooperative relation with the lugs 14 and 34 upon their respective brackets, the trainman is enabled to apply great force to the door, so that it may be brought to fully locked position even though it may be considerably warped. In a similar manner the removable lever may be manipulated to pry the door open in the event it should stick or become frozen in closed position by ice or snow.

20. I claim:

1. A car door mechanism for railway hopper cars including, in combination with a door hinged to the car body, a plurality of brackets one of which is mounted on the door and the other on a side sheet of the hopper, the said bracket mounted upon the door having a portion projecting outwardly beyond the side of the hopper, and a door locking member slidably mounted upon the said projecting portion of the bracket carried by the door, said locking member being adapted to engage the bracket carried by the hopper to prevent an opening movement of the door.

35. 2. A car door mechanism for railway hopper cars involving, in combination with a door hinged to the car body, a plurality of brackets one of which is mounted on the door and the other on the hopper, said brackets being provided with portions which overlap each other at a point spaced outwardly from the side of the hopper, and a slidable locking member mounted on one of said brackets and adapted to engage the other to lock the door in closed position.

3. A car door mechanism for railway hopper cars including, in combination with a door hinged to the car body, a plurality of brackets one of which is mounted on the door and the other on the hopper, and a locking member mounted on one of said brackets and adapted to engage the other bracket at a point spaced outwardly from the side of the hopper, said locking member being movable in the direction of its length.

40. 4. A car door mechanism for railway hopper cars including, in combination with a door hinged to the car body, a bracket secured to a side sheet of the hopper, a bracket mounted upon the door and having a portion which is disposed above and overlaps a portion of the said bracket secured to the hopper, and a locking member slidably mounted on the bracket carried by the door outwardly of the side of the hopper, said locking mem-

ber being adapted to engage the bracket secured to the hopper for maintaining the door in closed position.

45. 5. A car door mechanism including, in combination with a door hinged to the car body, a bracket secured to said door, a reinforcing member secured to said door and said bracket, said bracket being provided with a portion projecting outwardly beyond the side of the car, a locking member slidably mounted upon the said projecting portion of the bracket, and a bracket mounted upon the side of the car and adapted to cooperate with said locking member to maintain the door in closed position.

50. 6. A car door mechanism including, in combination with a door hinged to the car body, a reinforcing member secured to the door, a bracket provided with a plurality of flanges disposed at an angle to each other, one of said flanges being secured to said reinforcing member and the other to the door, said bracket being provided with a perforated housing, a bolt slidably mounted in said housing, and a bracket mounted on the side of the car and provided with an opening for receiving said bolt, said housing and said opening being spaced outwardly from the side of the car body.

55. 7. A car door mechanism including, in combination with a door hinged to the car body and having a marginal flange beyond the side of the car, a bracket secured to the door, said bracket being offset to clear said flange and being provided outwardly of said offset with a housing, a bolt slidably mounted in said housing, and a bracket secured to the car side for cooperating with the housing to maintain the door in closed position.

60. 8. A car door mechanism including, in combination with a door hinged to the car body, a bracket secured to the door and having a portion projecting outwardly beyond the adjacent side of the car, said bracket being provided at its outer end with means forming a seat for a removable prying lever and being formed adjacent said means with a housing adapted to receive a slidable locking member, a slidable locking member formed with a shoulder adapted to be engaged by a removable prying lever cooperating with said means, and a bracket mounted upon the adjacent side of the car and adapted to cooperate with said locking member to maintain the door in closed position, said last named bracket being provided with a portion forming a seat for a removable lever which is adapted to cooperate with said bracket carried by the door.

65. 9. A car door mechanism including, in combination with a door hinged to the car body, a bracket mounted upon the door, a rectilinearly movable locking device carried by said bracket, and means secured to the adjacent side wall of the car body for cooperat-

ing with said locking device to prevent an opening movement of the door, said bracket and said locking device being provided with shoulders adapted to be simultaneously engaged by a removable prying lever.

10. A car door mechanism including, in combination with a door hinged to the car body, a plurality of brackets one of which is secured to the car body and the other to the door, rectilinearly movable means mounted on one and adapted to engage the other of said brackets to prevent an opening movement of the door, said means and the bracket upon which it is mounted being provided with shoulders adapted to cooperate with a removable lever whereby said means may be moved to door releasing position.

11. A car door including, in combination with a door hinged to the car body, a bracket secured to the door and formed outwardly of the adjacent edge of the latter with a housing, a locking member slidably mounted in said housing, and a bracket secured to the car body for cooperating with said locking member to secure the door in closed position, said first named bracket being formed with a basal flange and a flange connecting said housing thereto.

12. A door mechanism for the hopper of a railway car including, in combination with a door hingedly associated with the hopper, a plurality of bracket members respectively secured to the door and to the side of the hopper, and a slidably mounted locking member engageable with said brackets adjacent a side edge of the door for supporting the door in closed position, said locking member and one of said brackets being provided with portions disposed outwardly of the said side of the hopper adapted to be simultaneously engaged by a removable prying lever for inducing movement of said member.

13. A door mechanism for the hopper of a railway car including, in combination with a door hingedly associated with the hopper, a plurality of bracket members one of which is secured to the door and the other to the side of the hopper adjacent a side edge of the door, and a slideable locking member mounted on one of the said brackets and adapted to engage the other bracket for supporting the door in closed position, said locking member and bracket on which it is mounted being provided with means simultaneously engageable with a removable prying lever for moving said locking member out of engagement with the other bracket.

14. A door mechanism for the hopper of a railway car including, in combination with a door hingedly associated with the hopper, a plurality of brackets one of which is mounted on the door and the other on the side of the hopper adjacent a side edge of the door, and a locking member slidably mounted on one of said brackets and adapted to engage the

other bracket to support the door in closed position, the lower portion of said member being provided with a surface engageable with said last-named bracket upon closing movement of the door for causing said member to move upwardly into position to operatively engage the said bracket.

15. A door mechanism for the hopper of a railway car including, in combination with a door hingedly associated with the hopper, a plurality of brackets one of which is mounted on the door and the other on the side of the hopper adjacent a side edge of the door, and a locking member slidably mounted on one of said brackets and adapted to engage the other bracket, said locking member being movable in the direction of its length at an angle to the hinge axis of the door, said brackets and member being cooperable to support the door in partially closed position and in fully closed position.

16. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket member rigidly secured to the outer side sheet of the hopper adjacent a side edge of the door and projecting beyond the plane of the closed door, the projecting end of said bracket having a portion which extends outwardly beyond the adjacent side sheet of the hopper at an angle to the latter and is provided in its upper surface with an aperture, an arm member rigidly secured to the door and extending outwardly beyond the outer side sheet of the hopper in proximity to the projecting end of said bracket, said arm being provided with an aperture adapted to register with the aperture of the bracket when the door is in closed position, and a member movable into the apertures of said arm and bracket for maintaining the door in closed position.

17. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket member rigidly affixed to the outer side sheet of the hopper adjacent a side edge of the door and projecting beyond the plane of the closed door, the projecting end of said bracket having a plurality of angularly disposed portions, one of said portions extending laterally of said outer side sheet and being provided with an aperture, an arm rigidly secured to the door and extending outwardly beyond an edge thereof in proximity to the projecting end of said bracket, said arm being provided with an aperture adapted to regis-

ter with the aperture of the bracket when the door is in closed position, and a member movable into the apertures of said arm and bracket for maintaining the door in closed position.

18. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket mounted upon the hopper comprising a basal plate having laterally offset portions one of which engages and is secured to the outer side sheet of the hopper and the other of which projects outwardly beyond the plane of the closed door, said last-named portion being provided with an angularly disposed laterally extending portion provided with an aperture, an arm member rigidly secured to the door and extending outwardly beyond the outer side sheet in proximity to the apertured portion of said bracket, said arm being provided with an aperture adapted to register with the aperture of the bracket when the door is in closed position, and a member movable into the apertures of said arm and bracket for maintaining the door in closed position.

19. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket mounted upon the hopper, said bracket having laterally offset portions one of which is secured to the outer side sheet of the hopper and the other of which extends beyond the plane of the closed door, said last-named portion having a substantially vertically disposed portion and a portion extending laterally and outwardly of the latter, said lateral portion being provided with an aperture, and an arm member rigidly secured to the door and adapted to be disposed in overlapping relation to said bracket, said arm being provided with an aperture adapted to register with the aperture of the bracket when the door is in closed position, and a member movable into said apertures of the arm and bracket for maintaining the door in closed position.

20. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket mounted upon the hopper, said bracket having laterally offset plate portions one of which is secured to the outer side sheet of the hopper and the other of which projects beyond the plane of the closed door in a plane substantially normal to the hinge axis of the door, said last-named portion being provided with an angularly disposed laterally extending portion provided with an aperture, an arm rigidly secured to the door and extending outwardly beyond a side edge thereof and adapted to be disposed in overlapping relation to the projecting portion of said bracket, said arm being provided with an aperture adapted to register with the aperture of the bracket when the door is in closed position, and a member movable into the apertures of said arm and bracket for maintaining said door in closed position.

21. In a railway car, the combination with a hopper having a lading discharge opening, said hopper being defined by inner and outer side sheets and an inclined floor sheet, of a hinged door for closing the opening, the door being arranged to swing to open position under the influence of gravity, an arm rigidly secured to the door and projecting beyond a side edge thereof, the projecting portion of said arm being provided with an aperture, a rectilinearly movable locking member mounted in said aperture and adapted to depend below the arm, and a bracket member rigidly secured to the outer side sheet of the hopper and having a portion adapted to underlie the projecting end of the arm when the door is in closed position, said portion of the bracket having a relatively wide upper surface with an opening therethrough, said upper surface terminating in an inclined approach plane engageable by said movable member to elevate the latter when the door is moved to closed position and said movable member being adapted to move downwardly into the opening in the bracket to maintain the door in closed position.

22. In a railway car, the combination with a hopper having a lading discharge opening, said hopper being defined by inner and outer side sheets and an inclined floor sheet, of a hinged door for closing the opening, the door being arranged to swing to open position under the influence of gravity, a stiffening beam secured to the door adjacent its free edge and having a portion projecting outwardly from the outer face of the door, an arm secured to said beam and having a portion disposed outwardly of a side edge of the door, said portion of the arm having a passageway defined by a plurality of walls substantially normal to the outwardly projecting portion of the beam, a bracket secured to the outer side sheet of the hopper and having a portion provided with an aperture adapted to register with the passageway in said arm when the door is in closed position, and a member mounted in said passageway and adapted to be moved rectilinearly into the

120

125

130

opening in the bracket for supporting the door in closed position.

23. In a railway car, the combination with a hopper having a lading discharge opening, said hopper being defined by inner and outer side sheets and an inclined floor sheet, of a hinged door for closing the opening, the door being arranged to swing to open position under the influence of gravity, a stiffening beam secured to the door adjacent its free edge, an arm secured to said beam and having a portion disposed beyond a side edge of the door, said portion of the arm being formed with an opening, a rectilinearly movable locking member disposed within said opening, a bracket member rigidly mounted upon the outer side sheet of the hopper and engageable with said locking member to support the door in closed position, a keeper cooperable with said locking member for maintaining the latter in door-supporting position, and a wall rigid with said arm and provided adjacent its upper portion with means affording a support for said keeper.
24. In a railway car, the combination with a hopper having a lading discharge opening, said hopper being defined by inner and outer side sheets and an inclined floor sheet, of a hinged door for closing the opening, the door being arranged to swing to open position under the influence of gravity, a bracket rigidly attached to the hopper and projecting beyond the plane of the closed door, said bracket having a plate portion adapted to lie against and be secured to the outer side sheet of the hopper and the projecting end of said bracket including a relatively broad flat portion lying at an angle to the said outer side sheet, a stiffening beam secured to the outer face of the door, an arm rigidly secured to said stiffening beam and extending outwardly from the side of the door, said arm being adapted to pass closely above the projecting end of the bracket when the door is moved to closed position, apertures respectively formed in said arm and bracket, and a rectilinearly movable locking bolt adapted to be moved into said apertures for supporting the door in closed position, and means mounted upon said arm and cooperable with said bolt for maintaining the latter in door-supporting position.
25. In a railway car, the combination with a hopper having a lading discharge opening, said hopper being defined by inner and outer side sheets and an inclined floor sheet, of a hinged door for closing the opening, the door being arranged to swing to open position under the influence of gravity, means for supporting the door in closed position involving apertured members respectively carried by the hopper and door and adapted to be disposed in overlapping relation when the door is in closed position, a locking member movable into the apertures of said members for supporting the door in closed position, and means for maintaining the locking member in door-supporting position, said means involving a pivoted cam the axis of rotation of which is disposed above and to one side of said locking member.
26. In a railway car, the combination with a hopper having a lading discharge opening, of a hinged door for closing the opening, the door being arranged to swing to open position under the influence of gravity, means for supporting the door in closed position involving apertured members respectively secured to the hopper and door adapted to be disposed in overlapping relation when the door is in closed position, a locking bolt slidably mounted in the aperture of one of said members and adapted to extend into the aperture of the other of said members to support the door in closed position, the lower portion of said bolt being provided with a surface adapted to engage said last-named member upon closing movement of the door for causing upward movement of said bolt whereby the latter may move under the influence of gravity into the aperture of said last-named member, said bolt and the bracket in which the latter is slidably mounted being respectively provided with laterally projecting means adapted to cooperate with a removable pry bar for moving said bolt upwardly out of door-supporting position.
27. In a railway car, the combination with a hopper having a lading discharge opening, of hinged door for closing the opening, the door being arranged to swing to open position under the influence of gravity, means for supporting the door in closed position involving apertured members respectively secured to the hopper and door adapted to be disposed in overlapping relation when the door is in closed position, a slidable locking bolt adapted to extend into said apertures for supporting the door in closed position, said bolt being provided with a shoulder adapted to form a lever seat, and means arranged below said shoulder to form a fulcrum for a removable lever whereby the locking bolt may be forced upwardly out of door-supporting position.
28. In a railway car, the combination with a hopper having a lading discharge opening, of a hinged door for closing the opening, said hopper being defined by inner and outer side sheets and an inclined floor sheet, of a hinged door for closing the opening, the door being arranged to swing to open position under the influence of gravity, an arm secured to the door and extending outwardly beyond the outer side sheet of the hopper, a bracket secured to the said outer side sheet and projecting beyond the plane of the lading discharge opening, said bracket being adapted to underlie the outer end of said arm when the door is in closed position and being adapted to form an abutment for the arm to limit sag-

ging of the door, apertures formed in said arm and bracket adapted to register when the door is in closed position, and a sliding locking bolt movable into said apertures to support the door in closed position.

29. In a railway car, the combination with a hopper having a lading discharge opening, said hopper being defined by inner and outer side sheets and an inclined floor sheet, of a hinged door for closing the opening, the door being arranged to swing to open position under the influence of gravity, means for supporting the door in closed position involving apertured members respectively carried by the hopper and door and adapted to be disposed in overlapping relation when the door is in closed position, a locking member movable into the apertures of said members for supporting the door in closed position, and a pivoted cam for maintaining the locking member in door supporting position, the pivotal axis of the cam being disposed to one side of the center line of the path of movement of the locking member and the latter being provided with a beveled portion engageable with the cam when in door supporting position.

In testimony whereof I affix my signature.
BYERS W. KADEL.
